ELECTRIC BOND AND METHOD OF ATTACHMENT FOR RAIL JOINTS

Edward A. Everett, Long Island City, N. Y.

Application April 12, 1933, Serial No. 665,737

7 Claims. (Cl. 173—280)

This invention relates to connectors for electric conductors to railway rails, such as may be used in the electric bonds for rail joints, and is a continuation, in part, of my co-pending application, Serial No. 641,596, filed November 7, 1932, now Patent 2,074,379 March 23, 1937.

The objects of the invention are to provide an improved attachment for conductors to rails in which an electric circuit is to be established to 10 the rail. A particular object of the invention is to provide an attachment for a conductor to a bottomed hole in the rail by means of a plug to which the conductor is secured, the plug being expanded, upset or spread where it engages the 15 end of the hole, producing the tightest grip between the plug and the rail at the bottom of the hole. Another object of the invention is to provide an attaching plug for a rail hole in which the hole has a conical end as produced in the ordinary 20 drilling of holes, and the plug is provided with a flat nose which expands or upsets as it is driven against the conical end of the hole or rail cavity. Another object of the invention is to provide a 25 plug attachment for a rail hole having a conical end and in which the plug has a flat nose softer than the body of the plug, which flat nose is driven against the conical end of the hole. Another object of the invention is to provide an attachment for a rail hole having a conical end comprising a 30 terminal with an eye to which the conductor is secured and a flat nosed plug driven through said eye into the rail hole, and another object is to provide a rail attachment for a conductor that can readily be removed from the rail and replaced. 35

Other objects of the invention will be more particularly understood from the following specification and from the accompanying drawing, in which:

Fig. 1 is a plan view of an electric bond for 40 bonding rail joints embodying my invention;

Fig. 2 is a sectional view of an eyelet type of terminal with the attaching plug therein;

Fig. 3 is a sectional view of a combined terminal and plug having a flange construction for retaining the conductor in place;

Fig. 4 is a side view of a terminal having a stranded conductor applied to a sectioned portion of rail having a conical ended hole in which the plug of the terminal is upset or expanded, and

Fig. 5 is a sectional elevation of a rail and splice bar showing the application of the connector to the head of the rail.

Track circuits are used on railroads for block signalling purposes and for other purposes and 55 in order to maintain a continuous circuit from

rail to rail it is necessary to provide an electric bond between the abutting ends of the rails so that there may be no interruption in the electric circuit. The rails are subject to expansion and contraction due to variations in temperature and the bond which connects the rail ends must be flexible so as to adjust itself for variations in the distance between the connections. Bonds for this purpose have been applied to the head of the rails located over the top of the splice bars and they 5 have also been located to extend outside the splice bars and connected to the web of the rail. The electric bonds in this invention may be applied either to the head of the rail or to the web of the rail, but in most of the illustrations 10 the application to a short bond for the head of the rail has been used.

As illustrated in the drawing the bond comprises a flexible or stranded conductor which, as shown, is secured at its ends to terminals made 15 in the form of eyelets or grommets, which have a hollow core for receiving the attaching pin and which are provided with flanges to enclose the flexible conductor. The plug may also be made integral with the terminal or suitably secured to the conductor.

The eyelet or terminal of the conductor is secured to the rail by a pin or plug which engages the aperture of the eyelet with a driving fit and which enters a hole in the rail. The rail hole is 20 drilled by the usual twist drill with a conical point which makes a conical ended hole. The plug is hardened on the outer or driving end but has a comparatively soft flat nose or end which engages the conical bottom of the rail hole in 25 which it is driven and is thereby expanded under the driving force to form its tightest engagement at the bottom of the hole and also to form a seal between the rail and the plug.

In the drawing, 11 is the flexible conductor 40 which, as shown in Fig. 1, is laminated. This conductor at one end is attached to the terminal or eyelet 12 and at the opposite end is attached to the eyelet 13. The eyelet comprises a bobbin 16 having a bottom flange 17 and a top flange 18, 45 the latter being provided with an extension 19 which is spun over or otherwise formed to enclose an annular space around the bobbin 16. In the center of each eyelet the plug 14 is inserted, having the flat face or nose 15 which enters the 50 hole in the rail. The flange 19 is deflected as indicated at 22 to provide an outlet for the conductor from the terminal.

One method of connecting the terminal to a bottomed hole in the rail is indicated in Fig. 4 55

in which 39 is the rail which is provided with a hole or cavity having a conical end as indicated at 38. The plug 14, Fig. 2, is provided with a flat nose at 15 and is hardened with a tapering 5 hardness from the end 14 towards the end 15 so that the body of 14 is comparatively hard and the nose 15, below the line x, is comparatively soft. When this pin is driven into the conical ended hole 38 the driving force spreads or upsets 10 the soft nose 15 outwardly as indicated in somewhat exaggerated form at 15a and 15b, Fig. 4, while the hardened body of the pin prevents the body from materially expanding. This has the effect of causing the pin or plug to secure its 15 principal grip in the hole at the bottom, thereby improving the connection and insuring a reliable grip in holes of different depth.

It is found in practice that the flat nosed plug with the air pocket at the conical end of the hole 20 does not have as great a tendency to "bounce back" when over driven as in holes where the air pocket is not provided. In order to facilitate the removal of the plugs from the hole by a side blow from the hammer, the diameter of the hole 25 is greater than its depth so that the stout body of the plug is dislodged as a unit. A steel plug, properly tempered, will spread at the edges 15 but will not fill the space 38, Fig. 4.

The plug and eyelet attachment enables the 30 eyelet to be placed tightly against the rail head while the plug adjusts itself to holes of different depths. The eyelet is made from light, bendable stock to enclose the conductor and the projecting end of the plug receives the hammer and protects the eyelet from being mutilated when driving or when in use. The outer end of the plug is hardened and tapered so that it will not spread under the hammer and so that it will deflect objects from the side.

40 It will be noted from Fig. 2 that the body of the eyelet, or terminal, is cylindrical and the eye of the conductor is also cylindrical to fit the eyelet. The flanges project at right angles from the cylindrical stock and are comparatively light and 45 bendable to enclose the conductor, and one at least is formed integral with the cylindrical body.

The flanges of the terminal have tapering edges which form a rounded, or button like, terminal when installed that is capable of deflecting objects in its path that may be trailing from a 50 passing train.

When the attachment shown in Fig. 5 is applied to the ball of the rail, the solid plug fills the drilled hole as completely as the undrilled portion of the rail, except for the space 38 between the flat nose of the plug and the conical end of the hole. The load sustaining properties of the rail in compression are not materially affected by this type of attachment.

60 The construction illustrated in Fig. 3 embodies the plug and the terminal in one piece, the flat nosed plug 15c extending from the body 45 which clamps the conductor 21 by the flanges 19 as indicated in dotted outline on the drawing. The 65 plug 15c is driven into the rail similar to plug 15.

The pin or plug 15 has been described as a driving fit in the terminal and in the rail hole. It should be noted that the plug and the eye of the bond are produced in a manufacturing 70 establishment and there is no difficulty in securing a tight driving fit between these parts. The holes that are drilled in the rail are not always uniform and cannot be produced with the same precision as the holes in the eyelets. A reason for this is 75 that drills are not always properly sharpened,

for instance, the point is sometimes off centre and the drill makes a hole slightly larger than normal into which the plug may be forced without driving. Also when the same hole is used several times it tends to become somewhat enlarged. Holes of this character are herein referred to as being of a driving fit for the plug and the driving force is maintained upon the plug until it expands and becomes a tight fit in the hole.

5 The end elevation in Fig. 5 shows the rail 51 with the splice bar 52 and with the terminal of the conductor 18 attached thereto by the plug 14 which is driven through the terminal 18 and has its flat nose 15 expanded or upset where the conical end of the rail hole begins. In Figs. 2 10 and 3 it will be noted from the section, that the conductor 21 is laminated corresponding to 11 in Fig. 1, while in Fig. 4 the conductor 36 is made in the form of a stranded cable.

The present invention is directed to the method 20 of attaching the conductor to the rail by a bottomed hole in the rail. The type of conductor and the type of terminal used are merely typical of a variety of constructions that may be used for this purpose. For the purpose of the attachment it is merely necessary to secure the conductor to the plug in some satisfactory manner. The plug as it is upset in the hole increases its grip and enables the driving force to be increased without increasing the tendency to rebound. In 30 practice it is found that the plug will spread in the rail hole and change its contour even when the plug is softer than the rail. The tempering of the plug helps to locate the spreading at the soft nose, but untempered plugs can be successfully used provided that they will spread under the driving force. The best results in the spreading of the plug are obtained when the nose is "square" and the edges are fairly sharp. If 35 the edges are beveled the tendency to spread for 40 the same amount of driving is reduced.

At this time it is pointed out that it is necessary to remove the connection from the rail in case of replacements and it is desirable that this be done without the use of special tools. This 45 operation is made possible by the use of the solid pin which connects the terminal to the hole in the rail as indicated in the various figures. The portion of the pin which is outside the hole is much longer than the portion in the hole and when deflected sideways by the hammer it can easily be driven from the hole without mutilating the hole so that a new bond can be installed in the place of the old one.

In the various types of rail bonds described it 55 is to be understood that the several features illustrated may be interchanged, that other types of rail attachments may be used and that the device itself, while referred to as a rail bond for insuring the conductivity of an electric circuit 60 around rail joints, is also applicable for making connections to the rail for any purpose. Any theories expressed in this specification are based upon present knowledge and appear to be supported by tests but it is understood that in the 65 light of later knowledge these theories may be subject to modification.

Certain matter divided out of this application is included in application 700,841 of December 4, 1933 and application 56,865 of December 31, 1935.

Having thus described my invention, I claim:

1. In combination a rail with a cylindrical hole having a conical end, a flexible conductor and a terminal secured to the conductor, said terminal having an eyelet and a solid plug with a flat nose

5 applied through the eyelet to the cylindrical rail hole, said plug being a driving fit in the eyelet and in the rail hole and said nose being softer than the body of the plug and engaging the conical end of the hole and spreading during the driving operation.

2. The method of attaching a conductor to a rail comprising drilling a hole in the rail with a conical bottom, and applying to the rail hole a 10 plug with a driving fit having a flat nose and connected with the conductor, the flat nose of said plug being upset in the rail hole as the plug is driven in place against the conical end of the hole.

15 3. In combination, a rail with a cylindrical hole having a conical end, a conductor, a plug with a flat nose secured to the conductor and driven into the rail hole, said nose being softer than the body of the plug and being driven against the 20 conical end of the hole.

4. In combination, a rail having a cylindrical hole with a conical end, a conductor with a terminal having an eye substantially the same diameter as the rail hole, said terminal being placed 25 against the rail and a plug of a driving fit for the rail hole driven with a driving fit through said eye by its projecting end into the rail hole to secure the terminal to the rail and characterized by

a flat nose on the end of the plug entering the rail hole which is upset in the hole where it engages the conical end of the hole.

5. In combination, a rail with a cylindrical hole having a conical end, a conductor having a 5 terminal with an eye of substantially the same diameter as the rail hole and a plug driven with a driving fit through said eye and into the rail hole and being a driving fit in the rail hole, characterized by a flat nose on the end of the plug entering 10 the rail hole which is upset in the hole where it engages the conical end of the hole.

15 6. The method of attaching a conductor to a railway rail comprising drilling a hole in the rail with a conical bottom, securing the conductor to a terminal and providing said terminal with a plug having a flat nose for driving into the rail hole and causing the spreading of the nose of the plug in the hole by driving it against the conical 20 end of the hole.

25 7. The method of attaching a conductor to a railway rail comprising drilling a hole in the rail with a conical bottom, securing the conductor to a terminal having an eye and driving a plug with a flat nose through said eye and into the rail hole 25 and causing a spreading of the nose of the plug as it is driven against the conical end of the hole.

EDWARD A. EVERETT.
